UNITED STATES PATENT OFFICE

JEFFROY MONZROLL, OF DALHOUSIE, NEW BRUNSWICK, CANADA

WRENCH

Application filed February 18, 1929, Serial No. 340,976, and in Canada May 21, 1928.

The present invention relates to improvements in the construction of wrenches and has for its primary object the provision of a wrench which shall be capable of quick and accurate adjustment.

Another object of the invention is the provision of a wrench of the above character designed to tightly engage a pipe or similar object.

10 A further object of the invention is the provision of a wrench of the above character which will be relatively simple and durable of construction and which can be conveniently operated.

15 Other objects and advantages of the invention will become apparent as the description progresses.

In the accompanying drawings forming a part of this specification and in which like reference characters are employed to designate corresponding parts throughout the same:

Figure 1 is a side elevational view of the wrench,

25 Figure 2 is a longitudinal sectional view through the same,

Figure 3 is a transverse section taken on the line 3—3 of Figure 1,

Figure 4 is a similar view taken on the line 30 4—4 of Figure 1, and

Figure 5 is a similar section taken on the line 5—5 of Figure 2.

Referring to the drawings, wherein for the purpose of illustration is shown a preferred embodiment of the invention, the numeral 10 generally designates an elongated tapered bar having an upstanding U-shaped casing 11 formed on its forward end. The forward extremity of the bar 10 is also formed with a fixed jaw 12, preferably serrated at its outer work engaging face. On its upper forward surface, the bar 10 is formed with transversely opposed longitudinal flanges 13 forming therebetween a longitudinal groove.

45 Slidably fitted through the casing or frame 11, for longitudinal adjustment, is a shank 14 formed at its outer end with a laterally projecting jaw 15 serrated on its inner face and adapted to co-operate with the fixed jaw 12. The upper side of the shank 14 is pref-

erably serrated to form a toothed rack 16, the purpose of which will be later described.

Pivottally connected with the rear or inner end of the shank 14 is a lever 17 formed with a raised head 18 adapted to receive the inner end of the shank. The shank is associated with the lever head through the medium of a transverse pivot pin 19, as shown to advantage in Figure 2. The lower portion of the head 18 is formed with an offset cam 20 projecting into the groove formed between the flanges 13 and rockable thereon. The inner portion of the head is formed with an upwardly directed shoulder 21 designed to engage the lower end of the shank 14 in gripping position.

Pivoted in the upper portion of the frame 11, to engage the toothed rack of the shank, is a crescent shaped pawl 22 having the end portions projecting downwardly toward the shank. The outer or rear end of the pawl is normally urged to a downward rack engaging position by means of a double spring 23, as shown to advantage in Figure 2. The opposed or forward end of the pawl carries an arcuate handle 24 projecting outwardly of the frame for selectively disengaging the pawl from the shank.

The lever 17 is provided with a lateral bevelled cutting rib 25 designed to co-operate with one of the flanges 13 to form a cutting implement, as shown to advantage in Figure 5.

In operation, the lever 17 is initially elevated, as illustrated in Figure 1, and the handle 24 of the pawl is depressed to disengage the pawl from the rack 16 of the shank. The jaw carrying shank and lever 17 are then actuated longitudinally to pipe or other work engaging position. The pawl lever 24 is then released so that the rear edge of the pawl engages the rack 16 to prevent longitudinal extension of the shank. The lever 17 is then swung inwardly toward the extension of the bar 10, swinging about the cam 20 as a fulcrum. This action results in tilting the shank 24 at an upward angular inclination with respect to the bar 10 so that the adjustable jaw 15 is forced tightly against the work. Thus, the wrench can be

conveniently manipulated with one hand and effectively grip a pipe or other object.

It is to be understood that the form of my invention herein shown and described is to be taken as a preferred example of the same, and that various changes as to the shape, size, and arrangement of parts may be resorted to without departing from the spirit of the invention or the scope of the subjoined claims.

Having thus described my invention, I claim:

1. A wrench including an elongated bar having a jaw formed on its forward end, a laterally extending frame formed on the bar, a shank slidable through said frame longitudinally on the bar, a jaw formed on the forward end of the shank, a lever pivoted to the shank adapted to tilt the same in gripping position, a pivoted pawl mounted in the outer portion of the frame having one end engageable with the shank to lock the same against extended movement, means resiliently urging the pawl into shank engaging position, and means for manually tilting the pawl out of engagement with the shank.
2. In a wrench of the character described, the combination of a body bar having a fixed jaw formed on one end thereof, a guide frame mounted on the body bar, a shank slidable through the guide frame formed with teeth in its outer edge, a jaw formed on the forward end of the shank adapted to co-operate with the fixed jaw of the body bar, a lever pivotally connected to the inner end of the shank, a cam formed on the inner end of the lever rockable on the inner side of the body bar to tilt the shank in gripping position, and a pivoted pawl mounted in the outer portion of the frame having means for normally urging one end thereof into contact with the teeth in the shank, the said pawl being arranged so that the shank will be urged more intimately therewith when the shank is tilted into gripping position to prevent sliding movement of the shank.

In witness whereof I have hereunto set my hand.

JEFFROY MONZROLL.
